(57) **CLAIM**

The ornamental design for a top bracket for mounting device, as shown and described.

DESCRIPTION

FIG. 1 is a perspective of the top bracket for mounting device in accordance with the present invention;

FIG. 2 is a front view of the top bracket for mounting device;

FIG. 3 is a back view of the top bracket for mounting device;

FIG. 4 is a top view of top bracket for mounting device;

FIG. 5 is a bottom view of the top bracket for mounting device; and,

FIG. 6 is a left side view of the top bracket for mounting device, the right side view being a mirror image thereof.

The broken lines in the disclosure of FIGS. 1-6 is understood to be for illustrative purposes and forms no part of the claimed design.
